MAX PAUL ERNST HOHN, OF DRESDEN, GERMANY, ASSIGNOR TO THE FIRM "UNIVERSALLE" CIGARETTENMASCHINEN-FABRIK J. C. MULLER & CO., OF DRESDEN, GERMANY

SHARPENING-ROLLER ARRANGEMENT FOR THE REVOLVING SICKLE KNIVES IN CIGARETTE-ROD MACHINES

Application filed November 29, 1927, Serial No. 236,548, and in Germany December 3, 1926.

The sickle or crescent-shaped knife which serves to cut through the continuously advancing cigarette rod must constantly be kept sharp. On this account the sickle knife, according to known suggestions, is brought into engagement with a sharpening roller or grinding disc after the termination of each cut, the said roller or disc being so adjusted that the edge of the sickle knife is sharpened thereon in passing it.

The sickle knife may be carried by a carrier which merely executes a circulating movement, so that the sickle knife always moves in the same plane. In this case the sickle knife carrier must be moved, during the execution of the cut, in the direction of feed of the cigarette rod and with the velocity of feed thereof. There are however also constructions known wherein the sickle knife carrier executes such a movement that the sickle knife moves in a helical line or executes a vibrating or wobbling movement, these movements being so arranged, that the sickle knife, during the cut, follows the cigarette rod in the direction of feed and at the velocity of feed.

For both cases various suggestions have already been made with regard to the arrangement of the sharpening roller. In all cases however the sharpening roller is either stationary in position, though rotatably supported, and is obliquely placed in such a way that the sickle knife, with its cutting edge, is sharpened as it moves past the sharpening roller, or else the sickle knife is mounted upon a controlled carrier, which effects substantially a displacement of the sharpening roller in the direction of feed of the cigarette rod, so that the sharpening roller, at the appropriate moment, is moved up to the cutting edge of the sickle knife and then follows the direction of feed of the cigarette cord by virtue of a corresponding displacement in the movement of the sickle knife.

The present invention consists in an arrangement of the sharpening roller which admits of being employed for both kinds of sickle knife guiding, the sharpening roller or grinding disc being so arranged on a circulating carrier that at each revolution of the

carrier it comes once into engagement with the cutting edge of the revolving sickle knife. In this way it is possible not only to let the sickle knife rub over the grinding surface of the sharpening roller, but also at the same time to guide the sharpening roller past the cutting edge of the sickle knife in the opposite direction. By this means the time of engagement is shortened, and at the same time the sharpening work is improved.

The sharpening roller carrier and the sickle knife carrier are preferably carried by parallel shafts revolving in the same direction and with the same velocity.

These shafts may be lodged in a common closed bearing casing, in which the driving means, originating from a common driving shaft, are also lodged, so that all the driving members are immersed in an oil bath enclosed in the bearing casing.

If the sickle knife carrier is arranged so as to be obliquely adjustable upon its driving shaft, in well known manner, the sickle knife will execute a vibrating or wobbling movement by virtue of which it can follow the direction of feed, with the velocity of feed, when cutting the cigarette rod. If the sharpening roller carrier is then at the same time made in more than one part and the parts are adjustable relatively to one another, the sharpening roller or grinding disc can then be so adjusted that during the circulating rotation of the sharpening roller carrier it follows the vibrating movement of the sickle knife at the moment when the two parts (sharpening roller and sickle knife) come into mutual contact. In this case it is advantageous to arrange the grinding disc carrier on its shaft in a longitudinally slideable but non-rotatable manner and to hold it fast by means of a fork which dips into an annular groove in the carrier, the fork being carried by a screw-threaded spindle which is arranged parallel to the carrier shaft, and by the rotation of which the longitudinal displacement of the carrier can be effected, even when the machine is working.

The accompanying drawings serve for the further elucidation of the invention:

Figure 1 shows the arrangement as a whole, seen from above;

Figure 2 is a longitudinal sectional elevation on the line 2—2 in Figure 1;

5 Figure 3 is a cross-sectional elevation on the line 3—3 in Figure 1;

Fig. 3^a is a sectional detail along lines 3^a—3^a of Fig. 3 looking in the direction of the arrows;

10 Figure 4 is a view of a detail.

The sickle knife carrier 1, which carries the sickle knife 2, embraces with two eyes 3 a horizontal bolt 4, which is kept rotatably caught in a bearing eye 5. The bearing eye 5 is mounted on the end of the knife carrier shaft 6. By the aid of the bearing eyes 3 and 5, an oblique adjustment of the knife carrier in relation to the longitudinal axis of the knife shaft 6 is possible. The fixing of 15 the knife carrier in the desired position is effected by tightening screw-threaded nut 7. Upon the knife carrier shaft 6 is mounted a bevel wheel 8, which meshes with a bevel wheel 9. This latter bevel wheel is carried 20 by a bush or sleeve, which is rotatably arranged upon a vertical spindle 10, and carries at its lower end a worm wheel 11, which meshes with a worm 12 on a driving shaft 13.

25 A grinding disc 14 is mounted with its spindle 15 rotatably in a bearing eye 16 which is carried by a cantilever 17. This cantilever terminates in a plate 18, which is connected by screws with a plate 19 on a hub member 20. For the screw-threaded bolts 18² secured 30 to the plate 18 or 19, concentric slots 18² are arranged in the other plate through which the bolts pass, so that relative adjustment of the plates 18 and 19 can take place. The hub member 20 of the grinding disc carrier is longitudinally displaceable on a shaft 21, but is keyed thereto by a key 23, which engages in a longitudinal groove in the internal cylindrical surface of the hub member 20. The shaft 21 is journalled in the same bearing 35 casing 24 in which the knife shaft 6 is journalled. Upon this shaft also is mounted a bevel wheel 8', which meshes with a bevel wheel 9', the sleeve of which is rotatably arranged about a vertical spindle 10', and at its lower end carries a worm wheel 11', which 40 meshes with a worm 12' on a driving shaft 13.

45 All the bevel wheels, worm wheels and worms are lodged in a closed casing 24, so that they are immersed in an oil bath lodged in the casing. The hub member 20 of the sharpening roller carrier is equipped with an annular groove 25, into which dips a fork 26, as shown in Figure 4. This fork is secured to the end of a screwthreaded spindle 27 by 50 means of a nut 27¹. The unthreaded part of the spindle 27 is guided in a bore in the casing 24, which runs parallel to the longitudinal direction of the shaft 21. The part 55 28 of the spindle 27 is equipped with a positioning nut 29, which is rotatably held

in a cover plate 30, screwed to the casing.

By rotating the positioning nut 29 the spindle 27 can thus be longitudinally shifted, in which case, owing to the fork 26, it takes the sharpening roller carrier with it. This adjustment can proceed while the machine is working.

60 The directions of rotation of the knife carrier and of the sharpening roller carrier are indicated in Figure 3 by corresponding arrows.

The bevel wheels and the worm wheels and worms are of the same dimensions, so that the shafts 8 and 21 are driven in the same direction and with the same velocity.

65 What I claim is:—

1. Sharpening means for the revolving sickle knife of a cigarette rod machine, comprising a revolving carrier, a sharpening roller rotatably mounted on said revolving carrier, and means for causing said sharpening roller to come into engagement with the cutting edge of the revolving sickle knife in each revolution.

70 2. Sharpening means for the revolving sickle knife of a cigarette rod machine, comprising two shafts arranged parallel to one another, means for rotating said shafts in the same direction and with the same velocity, a revolving carrier, mounted upon one of said shafts, a sharpening roller rotatably mounted on said revolving carrier, and a sickle knife carrier mounted upon the other of said shafts, said shafts and carriers being so arranged that the sharpening roller comes into engagement with the cutting edge of the revolving sickle knife once in each revolution.

75 3. Sharpening means for the revolving sickle knife of a cigarette rod machine, comprising a closed bearing casing, two shafts arranged parallel to one another, in said bearing casing, two bevel gears, one keyed upon each of said shafts, two additional bevel gears meshing respectively with said first-mentioned bevel gears, two worm wheels 80 adapted to drive said further bevel gears, two worms meshing respectively with said worm wheels, a common driving shaft upon which both of said worms are keyed, said worms, worm wheels and bevel gears being enclosed in said bearing casing and being so dimensioned that the two parallel shafts are rotated in the same direction and with the same velocity, a revolving carrier, mounted upon one of said shafts, a sharpening roller 100 mounted on said revolving carrier, and a sickle knife carrier mounted upon the other of said shafts, said shafts and carriers being so arranged that the sharpening roller comes into engagement with the cutting edge of the revolving sickle knife once in each revolution.

105 4. Sharpening means for the revolving sickle knife of a cigarette rod machine, comprising two shafts arranged parallel to one another, means for rotating said shafts in 110

115 120 125 130

the same direction and with the same velocity, a revolving carrier, mounted upon one of said shafts, a sharpening roller mounted on said revolving carrier, a sickle knife carrier mounted upon the other of said shafts, and means for adjusting the inclination of the sickle knife carrier to its shaft, the sharpening roller carrier consisting of relatively adjustable parts adapted to enable the sharpening roller to be correspondingly adjusted, so that the sharpening roller comes into engagement with the cutting edge of the revolving sickle knife once in each revolution.

5. Sharpening means for the revolving sickle knife of a cigarette rod machine, comprising two shafts arranged parallel to one another, means for rotating said shafts in the same direction and with the same velocity, a revolving carrier, slidably keyed upon one 10 of said shafts, said carrier being formed with an annular groove, a sharpening roller mounted on said revolving carrier, a sickle knife carrier mounted upon the other of said shafts, said shafts and carriers being so arranged that the sharpening roller comes into engagement with the cutting edge of the revolving sickle knife once in each revolution, a fixed nut, a screw-threaded spindle parallel to the carrier shaft, said spindle engaging 15 with said nut, means for rotating said spindle at will, and a fork mounted on said spindle and engaging in the annular groove in the carrier of the sharpening roller, to enable the position of the sharpening roller to be adjusted while the machine is working.

6. The combination with the revolving knife of a cigarette rod machine, of sharpening means, means for revolving said knife past a sharpening surface, means for guiding 20 said sharpening surface past the cutting edge of the knife in the opposite direction, to decrease the time of engagement of said knife and sharpening means, and adjustable means for varying the position of said sharpening 25 surface at will.

7. The combination with the revolving knife of a cigarette rod machine, of means for revolving said knife, a freely rotatable sharpening roller, means for revolving said 30 sharpening roller at the same speed as said knife, in the same direction, and adjustable means for varying the position of said sharpening roller, whereby said sharpening roller sweeping past said cutting knife in the opposite direction to the motion of said knife, comes into engagement with it once in each 35 revolution.

In testimony whereof I have signed my name to this specification.

60 MAX PAUL ERNST HOHN.
